ALARM CLOCK DEVICE

Richard Varley, New York, N. Y.; Edith Agge
Varley executrix of said Richard Varley, deceased

Application October 17, 1935, Serial No. 45,392

15 Claims. (Cl. 58—19)

This invention relates to an alarm clock device for the convenience of a person reclining in bed.

It is the natural custom of a person when awakened from sleep by the sound of an alarm clock to shut off the alarm and unless the person immediately arises, there is the natural tendency of the person to again fall asleep, with the result that the person oversleeps and is late in arising. I appreciate that alarm clocks have been devised whereby the clock initially sounds a soft audible alarm and if not shut off within a predetermined time, a louder and more violent audible alarm automatically operates. Such function has required changes in the alarm mechanism of a clock thus making the cost greater than that of an ordinary alarm clock, and even though two alarms are set off at predetermined intervals of time, it is possible for a sleeper to ignore them although awakened thereby, for they sound for a limited time only or by a single manual operation, the alarm may be shut off so that the second alarm never operates. It is therefore the purpose of this invention to continuously sound an audible alarm even though the sleeper may perform the manual act of shutting off the clock alarm when awakened thereby, to prevent the possibility of falling asleep thereafter.

Another feature of the invention resides in a bed side alarm device whereby the manual act of shutting off the alarm of an alarm clock serves to light a lamp and set into operation a soothing intermittent secondary audible alarm which will sound until a second manual act is performed.

Another feature of the invention is to provide a bed side alarm device wherein the lamp which may be a bed reading lamp cannot be conveniently turned off before retiring until the secondary alarm is set for operation which avoids forgetfulness on the part of a user to set the secondary alarm.

A further feature of the invention is the provision of a master control device by which an alarm clock, reading lamp, and secondary alarm may be conveniently controlled from a person lying in bed.

A further object of the invention is to provide a device of the above character which is compact and attractive in appearance so as not to detract from the artistic furnishings of a bed room in which it is intended for use.

With these and other objects in view, the invention resides in the novel construction, combination and arrangement of parts, the essential features of which are hereinafter fully described,

are particularly pointed out in the appended claims, and are illustrated in the accompanying drawings, in which:

Figure 1 is a perspective view of the alarm device. 5

Figure 2 is a side elevational view with parts broken away and shown in section.

Figure 3 is a front elevational view with parts shown in section, the alarm clock and its supporting cradle being shown in raised position in full lines, and in lowered position in dotted lines. 10

Figure 4 is a top plan view with the alarm clock and its cradle removed.

Figure 5 is a rear elevational view.

Figure 6 is a perspective view of the alarm 15 clock supporting cradle.

Figure 7 is a diagrammatic view of the electrical wiring.

Referring to the drawings by reference characters, the numeral 10 designates a flat rectangular shaped base which is hollow for the housing of electrical terminals and connecting wires for electrically connecting the several electric outlet sockets which are associated with the base and which will be hereinafter described. The 25 open body of the flat face is closed by a removable plate 11 secured in position by screws or like fastening elements 12 whereby access may be had to the parts enclosed within the base when desired. 30

Secured to the base 10 and rising upwardly therefrom is a rectangular shaped casing 13, the said casing being set back from the front of the base. The casing 13 is open at the top and is divided by a horizontal partition 14 to provide an upper compartment 15 and a lower compartment 16. The partition 14 extends forward of the casing 13 through a vertical slot 17 in the front wall thereof to provide a forwardly extending elevated platform 18. The partition 14 is constructed of metal and is bent downwardly and vertically to meet the top of the base 10. The downwardly bent portion constitutes a front wall 19 disposed in spaced parallel relation to the front wall of the casing 13, and together with the platform 18 and base 10, forms an open ended compartment 20. 35 40 45

The front wall of the casing 13 inwardly from the top thereof is provided with a curved cut away portion 21 to conform to the general shape 50 of the face of the alarm clock with which the device is intended for use. The rear wall of the casing 13 is similarly cut away as at 22 to expose the winding and setting knobs at the back of the alarm clock. 55

Mounted directly beneath the partition 14 and partly disposed within the lower compartment 16 and partly within the compartment 20, is a double push button snap switch 23 of the conventional construction, and which includes an "on" push button 24 and an "off" push button 25. The push buttons 24 and 25 extend through openings 26 in the partition 14. The push button 24 is disposed within the upper compartment 15 while the push button 25 is disposed just forward of the plane of the front wall of the casing 13 centrally of the slot or opening 17. In this type of two button snap switch, one button is always in an extended position, while the other is in a depressed position, the position of the buttons alternating relative to each other during the turning on and off of the switch.

Slidable vertically within the casing is a rectangular shaped cradle 27 open at its top and having arcuate shaped openings 28 in the front and rear which coincide with the cut outs 21 and 22 in the casing 13, and which register therewith when the cradle is in a lowered position as shown in Figure 1 of the drawings. The bottom of the cradle is provided with a depending socket or seat 29 for receiving the outer end of the push button 24. The push button 24 serves to support the cradle at all times for the weight of the same combined with the weight of the clock to be hereinafter described, is insufficient to overcome the spring action of the snap switch. The side walls of the casing act as guides for guiding the cradle during its up and down sliding movement. It will thus be seen that by pushing downwardly upon the "off" push button 25, the cradle may be lifted by the upward movement of the push button 24, and by pushing downwardly upon the cradle when the same is in a raised position, the "on" push button 24 will be depressed and the "off" push button 25 will move upwardly.

Supported by the cradle 27 is an alarm clock 30, the face and back of which are exposed through the openings 28. In the event that the alarm clock should be smaller than the cradle, suitable fillers may be inserted between the clock and the end walls of the cradle so as to prevent accidental tilting of the clock relative thereto. The alarm clock 30 is shown in the drawings as being of the electrically operated type, although alarm clocks of the winding spring actuated type may be used in connection with the invention without any changes in construction thereof. The alarm clock 30 is provided with the usual alarm setting and shut off button 31 which extends from the top of the clock casing. In the operation of this type of button, the manual pulling out of the button effects a setting of the alarm mechanism of the clock whereas a manual force applied in a downward direction to the button will cause the alarm to be stopped or prevent operation of the alarm clock. This same alarm control is present in spring actuated alarm clocks as well as the electrical type herein shown and described.

65 Mounted in the lower compartment 16 and opening through the rear of the casing 13 are electric outlet sockets 32 and 33, the socket 32 receiving a plug 34 carried by the free end of an electric cord 35 leading from the electric clock 30. The socket 33 receives a plug 36 carried by the free end of an electric cord 37 leading to a reading lamp 38' shown in the diagrammatic view in Figure 7. The lamp 38' may not necessarily be a reading lamp, but a wall or ceiling lamp within 75 a bed room, or the lamp 38' may be arranged in

parallel with other remote lamps in other rooms of a household for the purpose to be hereinafter explained.

The sockets 32 and 33 are electrically connected to a source of electric energy with which the device is adapted to be connected, and for this purpose an electric cord 38 has its conducting wires at one end respectively connected to binding posts 39 and 40 enclosed within the hollow base 10. The other end of the cord 38 carries a plug 41 which may be inserted into the socket of an electrical current supply system.

Mounted within the compartment 20 adjacent the left side thereof is an electric socket 42 which receives its supply of current from the main conductor cord 38 in a manner to be later described. Arranged in the same circuit as the socket 42 is a toggle snap switch 43 having a pivoted actuating lever 44. The switch is enclosed within the compartment 20 but the actuating lever 44 extends above the top wall 18 thereof forwardly of and to the left side of the push button 25. The lever 44 is provided with a flat disk 45, which when the actuating lever is swung to an "off" position, serves as an obstruction to prevent convenient access to the push button 25. The disk 45 when in obstructing position as shown in dotted lines in Figure 4 prevents free access to the manipulation of the push button 25, for to operate the same would require the unnatural forcible insertion of the finger between the disk and the adjacent front wall of the cradle 27. With this in mind, it is obvious that the disk prevents natural operation of the push button 25 to shut off the switch 23 unless the switch 43 is in an "on" position.

The switch 43 controls the secondary electrically operated alarm which is connected to the device through the socket 42. The secondary alarm includes an audible alarm preferably in the form of an electrically operated bell 46 which may be conveniently located in the room with the clock 30. The bell 46 is preferably of the soft tone or chime variety and has a less periodicity than the bell of the alarm clock 30. The bell 46 may be of the slow sounding type such as for instance, one that sounds at minute or half minute intervals. Although other types of sound instruments may be used in lieu of the instrument 46, I have found that the soft slow intermittent tones produced by this type of instrument are more pleasing to the ear of a person after being aroused from sleep by the violent and rapid sounding of the bell of the alarm clock 30. An electric cord 47 has one end connected to the sound instrument 46 and its other end connected to an electric plug 48 which is inserted into the socket 42.

The wiring of the several sockets and switch with the source of electric supply which enters through the cord 38 is enclosed within the hollow base 10, but in Figure 7 of the drawings, I have illustrated the wiring diagrammatically. The reading lamp circuit in which the socket 33 is arranged may be traced as follows: From binding post 39 through wire 49 to the socket 33, through the plug 36, cord 37, lamp 38', and return to the socket 33, wires 50 and 51 to the terminal 52 of the switch 23, through switch 23, wire 53, connected to the other terminal 52' of switch 23, and to the binding post 40. Thus when the push button 24 is down, the circuit to the reading lamp and to the socket 33 is closed, but when the push button 25 is down and the push button 24 up, the said circuit is open.

The electric circuit to the secondary alarm is

through the binding post 39, wire 54 to switch 43, through switch 43, when the same is in "on" position to wire 55, socket 42, plug 48, cord 47, bell 46 and return to socket 42, wire 56 to wire 51, terminals 52 and 52' of switch 23 to wire 53 to binding post 40. When the switch 43 is in "on" position and the switch 23 operated to "on" position by depression of the push button 24, the secondary alarm circuit will be closed and the bell 46 set in operation. The bell 46 may be conveniently located within a bed room with the device or a number of similar bells may be arranged in the same circuit in other rooms of a household to arouse not only the occupant of one room, but also the occupants of other rooms. If desired, a bell or other audible alarm device 56 may be arranged in the secondary alarm system by connecting the same with wires 50 and 55. When the bell 56 is incorporated in the circuit, the same may be used as a local secondary alarm signal whereas, the alarm instrument 46 connected with the device through the plug 48 and socket 42 may be located at some remote place.

In operation of the device, the alarm clock 30 is set for operation at a predetermined time before the user retires, the knob 31 being pulled upwardly to set position as shown in Figure 5. It is assumed that the push buttons 25 is in a down position and the switch 23 is therefore "off". The switch 43 is in an "on" position as shown in Figure 1, whereby the obstructing disk 45 is out of an obstructing position with respect to push button 25. As stated before, the device is adapted to be positioned on a table beside the bed of a user, and assume that the user after reclining upon the bed desires to read. It is only necessary for the user to reach over, press downwardly upon the clock without touching or distributing the set position of the alarm button, which force 40 presses the push button 24 and turns on the switch 23 and by reason of the downward movement of the push button 24, the push button 25 moves upwardly. Turning on of the switch 23 effects a closing of the reading lamp circuit, whereupon 45 the lamp 38' is illuminated. It will be remembered that the switch 43 is in an "on" position and that when the switch 23 is closed, the secondary alarm circuit in which the bell 46 is arranged will also be closed. In order to avoid the annoying sound of the secondary alarm bell 46, the user 50 operates the switch 43 to an open position, whereby the disk 45 is in an obstructing position with respect to the push button 25. The actuation of the switch 43 to shut off position opens the 55 secondary alarm circuit. When the user wishes to turn out the reading lamp to retire for the night, he cannot do so unless the switch 43 is turned "on" for it will be remembered that the disk 45 is obstructing access to the push button 25. The switch 43 is next turned on and with the obstructing disk 45 in a non-obstructing position, the user may depress the push button 25, causing 60 the switch 23 to be turned off, which moves the push button 24 upwardly which correspondingly moves the cradle and clock 30 to an elevated or raised position. The act of moving the disk 45 to an unobstructing position serves to set the alarm circuit for operation upon the subsequent turning on of the switch 23. When the rapid alarm of 65 the clock sounds for the awakening of the user, the user manually pushes downwardly upon the button 31 to shut off said alarm, and by a following through action of a slightly increased manual force, the elevated cradle 27 will move downward 70 and cause the depression of the push button 24

against its spring action which turns on the snap switch 23, thus simultaneously lighting the bed lamp 38' and operating the alarm circuit in which the slow sounding bell 46 is arranged. Should the user not arise upon the sounding of and shutting off of the alarm clock, he will be reminded thereafter by the slow intermittent tapping of the electrically actuated bell 46 and lighting of the lamp 38', which will act as a reminder and tend to prevent accidental falling asleep after the sounding of the initial alarm. After arising, the user may turn off the electric lamp 38' and the secondary alarm by the depression of the push button 23, or the switch 43 may be turned off and the light permitted to remain on. 15

For the purpose of providing illumination for the face of the alarm clock during the night, I provide a night light 57 which rises upwardly from the platform 18, and which receives its current from a socket 58 enclosed within the compartment 20. A switch 59 is provided for the turning on and off of the night light 57. In Figure 7 of the drawings, it will be seen that the socket 58 for the night light receives its electrical energy through wires 60 which are respectively connected to the binding posts 38 and 40. 20

Although I have described the tension on the shut-off button 31 of the alarm clock when in set position as being less than that of the "on" push button 24 of the snap switch 23 when in up 30 position, these relative tensions may be reversed, to assure that the "on" push button 24 is actuated from off position to "on" position during shutting off of the alarm mechanism of the clock. Such an arrangement avoids any possibility of 35 the shutting off of the clock alarm until the snap switch 23 is actuated to "on" position to close the auxiliary alarm circuit.

While I have shown and described what I consider to be the most practical embodiments of 40 my invention, I wish it to be understood that certain changes and alterations as come within the scope of the appended claims may be resorted to when desired.

Having thus described the invention, what I 45 claim as new and desire to secure by Letters Patent of the United States, is:—

1. An apparatus of the class described comprising in combination a primary time alarm device including an alarm setting and shut-off 50 mechanism, a secondary alarm means having a less periodicity than said primary alarm device, manually actuated control means for rendering said secondary alarm means operative and inoperative, means operable by the manual actuation of the shut-off mechanism from set to "off" position for actuating said control means to operative position to sound said secondary alarm means, and releasable obstructing means for preventing operation of said manually actuated control means when the latter is in operative position. 55

2. An apparatus of the class described comprising in combination, an alarm clock having a manually operated slideable alarm setting and shut-off mechanism, an electrical alarm device 65 including a circuit, a source of electrical energy for said circuit, an electrically operated sound instrument arranged in said circuit and having a less periodicity than said alarm clock, a switch arranged in said circuit, and means for slidably 70 supporting said alarm clock relative to said switch to cause actuation of said switch to "on" position upon manual actuation of said alarm setting and shut-off mechanism from its set position to its shut-off position. 75

3. An alarm device comprising in combination an alarm circuit, an electric lamp circuit, a source of electric energy for both circuits, a snap switch arranged in and common to said alarm circuit and to said electric lamp circuit, an alarm switch arranged in said alarm circuit, and obstructing means associated with the alarm switch for preventing access to the actuation of said snap switch to "off" position when said alarm switch is in "off" position.
4. An alarm device comprising in combination an alarm circuit, an electric lamp circuit, a source of electric energy for both circuits, a double push button snap switch having an "on" push button and an "off" push button, said push button snap switch being arranged in and common to said alarm circuit and to said electric lamp circuit, an alarm snap switch having a pivoted actuating lever arranged adjacent the "off" push button of said double push button switch, and an obstruction member carried by said actuating lever movable to an obstructing position with respect to the "off" push button when the alarm switch is in "off" position to interfere with the manual manipulation of said "off" push button when said alarm switch is in "off" position and to swing out of obstructing position relative to said "off" push button when said alarm switch is in an "on" position.
5. An alarm device comprising in combination, an alarm circuit having a source of electric energy, an electrically operated periodic audible alarm instrument arranged in said alarm circuit, a double push button snap switch having an "on" push button and an "off" push button, said push buttons being vertically disposed, an alarm clock supported by said "on" push button, means for guiding said alarm clock for up and down vertical movement, said alarm clock having a vertically slideable alarm control element at the top thereof, whereby manual actuation of said control element by a downward pressure to shut off the alarm will move said alarm clock downwardly and cause said "on" push button to be depressed to actuate the snap switch to close said alarm circuit to operate said periodic audible alarm instrument.
6. A device of the class described comprising in combination, a supporting stand, a double push-button snap switch mounted in a horizontal position upon said stand, said snap switch having an "off" push button and an "on" push button, both push buttons being vertically disposed, an electric circuit in which said switch is arranged, a source of electrical energy for said circuit, an electrical signal device in said circuit, an alarm clock supporting cradle supported by the "on" push button of said switch, and guide means on said stand for said alarm clock supporting cradle whereby manual downward pressure upon said cradle when said switch is in "off" position will effect a turning on of said switch.
7. A device of the class described comprising in combination, a supporting stand, a double push button snap switch mounted in a horizontal position upon said stand, said snap switch having an "off" push button and an "on" push button, both push buttons being vertically disposed, an electric circuit in which said switch is arranged, a source of electrical energy for said circuit, an electrical signal device in said circuit, an alarm clock supporting cradle supported by the "on" push button of said switch, guide means on said stand for said alarm clock supporting cradle whereby manual downward pressure upon
- said cradle when said switch is in "off" position will effect a turning on of said switch, a second snap switch arranged in said circuit and mounted on said stand and having a pivoted actuating member movable to an obstructing position forward of the "off" push button when said second snap switch is in "off" position, and movable to a position out of obstructing position with respect to said "off" push button when the second snap switch is in "on" position to facilitate free access to the manipulation of said "off" push button.
8. An apparatus of the class described comprising in combination an alarm clock having a manually depressible alarm shut-off mechanism, an electric circuit including a source of electrical energy, an electrically operated instrument in said circuit, an electric double push button snap switch arranged in said circuit and having an "on" push button and an "off" push button, and means for slidably supporting said alarm clock in an upright position upon said "on" push button, whereby the manual downward pressure exerted upon said shut-off mechanism will successively shut-off said alarm mechanism and actuate said "on" push button to close said electric switch.
9. An apparatus of the class described comprising in combination, an alarm clock having a manually depressible alarm shut-off mechanism, an electric circuit including a source of electrical energy, an electrically operated element arranged in said circuit, an electric double push button switch arranged in said circuit and having an "on" push button and an "off" push button, said push buttons being vertically disposed, and means for slidably supporting said alarm clock in a position of rest upon said "on" push button, whereby when said switch is in "off" position said alarm clock will be supported in an elevated position upon said "on" push button and upon a slight manual downward pressure upon the depressible alarm shut-off mechanism the same may be shut off, or upon an increased manual pressure thereto sufficient to overcome the tension of the snap switch, the alarm shut-off mechanism may be shut off and the "on" push button actuated to "on" position to close said switch and circuit.
10. In an apparatus of the class described, an alarm clock having manual depressible alarm shut-off mechanism, a stand, a double push button snap switch mounted on said stand having an "on" push button and an "off" push button, and means for slidably supporting said alarm clock upon said "on" push button, the tension of the snap switch being sufficient to support the alarm clock when the switch is in "off" position, whereby a single manual actuation of said shut off mechanism will actuate the same from set to shut off position and depress said "on" push button to "on" position to close said switch.
11. In an apparatus of the class described, an alarm clock having a manual depressible alarm shut-off mechanism, a stand, a double push button snap switch mounted on said stand having an "on" push button and an "off" push button, the manual force required to actuate said depressible alarm shut-off mechanism from set to off position being greater than the manual force required to actuate the "on" push button from off to on position, and means for slidably supporting said alarm clock upon said "on" push button whereby a single manual force applied to said shut-off mechanism will successively actuate said

"on" push button and shut off the alarm mechanism.

12. An alarm device comprising in combination, an alarm circuit, a source of electric energy for said circuit, a snap switch arranged in said circuit, an alarm switch arranged in said circuit, and obstructing means associated with the alarm switch for preventing access to the actuation of said snap switch to "off" position when said alarm switch is in "off" position.

13. An alarm device comprising in combination, an alarm circuit, a source of electric energy for said circuit, a double push button snap switch having an "on" push button and an "off" push button, said push button snap switch being arranged in said alarm circuit, an alarm snap switch having a pivoted actuating lever arranged adjacent the "off" push button of said double push button switch, and an obstruction member carried by said actuating lever movable to an obstructing position with respect to the "off" push button when the alarm switch is in "off" position to interfere with the manual manipulation of said "off" push button when said alarm switch is in "off" position and to swing out of obstructing position relative to said "off" push button when said alarm switch is in "on" position.

14. In a device of the class described, a supporting stand, a double push button snap switch mounted in a horizontal position upon said stand, said snap switch adapted to control an electric circuit and having an "off" push button and an

"on" push button, both push buttons being vertically disposed, an alarm clock supporting cradle supported by the "on" push button of said snap switch, and guide means on said stand for said alarm clock supporting cradle whereby manual downward pressure upon said cradle when said switch is in "off" position will effect a turning on of said switch.

15. In a device of the class described, a supporting stand, a double push button snap switch mounted in a horizontal position upon said stand, said snap switch adapted to control an electric circuit and having an "off" push button and an "on" push button, both push buttons being vertically disposed, an alarm clock supporting cradle supported by the "on" push button of said snap switch, and guide means on said stand for said alarm clock supporting cradle whereby manual downward pressure upon said cradle when said switch is in "off" position will effect a turning on of said switch, a second snap switch adapted to be arranged in the same circuit as the double push button snap switch and having a pivoted actuating member movable to an obstructing position forward of the "off" push button when said second snap switch is in "off" position and movable to a position out of obstructing position with respect to said "off" push button when the second snap switch is in "on" position to facilitate free access to the manipulation of said "off" push button.

RICHARD VARLEY.
